US0D1084029S

(12) **United States Design Patent** (10) Patent No.: **US D1,084,029 S**
(45) Date of Patent: ** Jul. 15, 2025

(54) **DISPLAY SCREEN OR PORTION THEREOF
WITH ICON**

- (71) Applicant: **Apple Inc.**, Cupertino, CA (US)
(72) Inventors: **Raphael Anselmo Hene**, Rellingen (DE); **Thorsten Quandt**, Hamburg (DE)
(73) Assignee: **Apple Inc.**, Cupertino, CA (US)
(**) Term: **15 Years**
(21) Appl. No.: **29/916,580**
(22) Filed: **Nov. 14, 2023**

Related U.S. Application Data

- (63) Continuation of application No. 29/821,166, filed on Dec. 28, 2021, now Pat. No. Des. 1,011,378, which is a continuation of application No. 29/757,209, filed on Nov. 4, 2020, now Pat. No. Des. 940,183, which is a continuation of application No. 29/727,614, filed on Mar. 12, 2020, now Pat. No. Des. 902,247, which is a continuation of application No. 29/700,168, filed on (Continued)

(57) **CLAIM**

The ornamental design for a display screen or portion thereof with icon as shown and described.

DESCRIPTION

The file of this patent contains at least one drawing/photograph executed in color. Copies of this patent with color drawing(s)/photograph(s) will be provided by the Office upon request and payment of the necessary fee.

The sole FIGURE shows a display screen or portion thereof with icon showing our new design.

The peripheral dashed broken lines illustrate a display screen or portion thereof and form no part of the claimed design.

**1 Claim, 1 Drawing Sheet
(1 of 1 Drawing Sheet(s) Filed in Color)**
